UNITED STATES PATENT OFFICE.

GEORGE C. BEIDLER, OF ROCHESTER, NEW YORK.

PHOTOGRAPHIC AND DEVELOPING APPARATUS.

1,171,495.

Specification of Letters Patent.

Patented Feb. 15, 1916.

Application filed January 3, 1910. Serial No. 535,839.

To all whom it may concern:

Be it known that I, GEORGE C. BEIDLER, a citizen of the United States of America, and resident of Rochester, in the county of 5 Monroe and State of New York, have invented certain new and useful Improvements in Photographic and Developing Apparatus, of which the following is a specification.

10 This invention relates to photographic and developing apparatus and particularly to an apparatus in which film is exposed to the action of light and in which novel means are provided for delivering the film from an exposing chamber to a receptacle designed to contain liquid which will act on the coated surface of the film, means being also provided for removing the film from the said receptacle and means being also 15 provided for removing that portion of the film which has been treated from a web of sensitized material.

20 A further object of this invention is to provide a photographing and developing apparatus provided with novel means for treating short sections of film which short sections are preferably delivered from the magazine or container to an exposing chamber and thereafter to a receptacle for containing developer, novel means being also provided for drawing the film from the receptacle and novel means being further provided for severing that portion of the film which has been treated from a web or roll 25 of sensitized material.

30 Furthermore, an object of this invention is to provide a photographic and developing apparatus in which a film or section of film may be exposed to the action of light and thereafter subjected to the action of liquid, for chemically treating the film, means being provided for severing the treated section of the film and for delivering the 35 said treated section of film to a receptacle designed to contain a fluid such as hypo or the like provided for the purpose of fixing the film by the well known photographic process, novel means being also provided for submerging the film in the last mentioned 40 receptacle.

45 A further object of this invention is to produce a photographing and developing apparatus having novel means for engaging and drawing a film or section of film from the 50 magazine or container and novel means for intermittently arresting and other means for

55 intermittently releasing the said mechanism and the invention further contemplates the provision of novel means designed to coact with the said mechanism for subjecting a 60 length of film to the action of developing fluid and to provide novel means for cutting the treated portion of film and removing it from the web or roll.

65 With the foregoing and other objects in view, the invention consists in the details of construction and in the arrangement and combination of parts to be hereinafter more fully set forth and claimed.

70 In describing the invention in detail, reference will be had to the accompanying drawings forming part of this specification wherein like characters denote corresponding parts in the several views, in which—

75 Figure 1 illustrates a view in elevation, the casing and part of the mechanism being shown in section; Fig. 2, illustrates a transverse sectional view taken on a line corresponding to the line 3—3 of Fig. 1; Fig. 3 illustrates a detail sectional view of the film 80 cutting and developing portion of the apparatus; Fig. 4 illustrates a top plan view thereof; Fig. 5 illustrates an enlarged detail view of a fragment of a carriage; Fig. 6 illustrates an end view of that portion of 85 the apparatus shown in Fig. 5; Figs. 7 and 8 illustrate the same elements as are shown in Fig. 4 but in different positions of adjustment; Fig. 9 illustrates an enlarged detail view from below of the controlling 90 device for the feeding rolls; Fig. 10 illustrates a detail sectional view, partly in elevation of means for feeding or moving film and for controlling the feeding means.

95 In these drawings 15 denotes a lens box which is applied to a bellows 16, the said bellows being in communication with an exposing chamber 17, the said bellows being shown as collapsible and capable of being confined within the exposing chamber when 100 it is desired to fold the film exposing portion of the apparatus for transportation. In Fig. 2, the bellows 16 is shown as supported on a door A⁶ which may close, the front of the box of which the exposing 105 chamber, the magazine or container and the base are a part and the said magazine or container 18 has guides 19 on its sides between which a bearing block 20 is slidable, the said bearing block having a longitudinal recess 110 21 designed to receive a spindle of the core 22 on which the film 23 is wound. The

container 18 has an opening in its top provided with a door or cover A⁷ to permit the roll of film to be applied to the supports and has an opening 24 at its upper corner in which is mounted an anti-friction roller 25 over which the film travels as it is drawn from the roll on the core. The front wall 26 of the container is employed as a backing for the film as it is drawn over the anti-friction roller 25 into position for exposure. A dark slide 27 is movable in a slot 28 and is provided for protecting the sensitized film from the action of light when the container is removed from the bellows frame 29 which bellows frame incloses the exposing chamber. The front frame 30 of the container has a flange 31, which is embraced by the bellows frame when the said container is applied thereto.

20 The apparatus is provided with a hollow base or box 33 having a light-proof joint 33^a with the container 18, the sides of said container extending below the floor 34 thereof. It will be seen from an inspection of 25 Fig. 1 that the container may be removed from the bellows frame 29 and from the base 33 for the purpose of gaining access to the interior of the base from the top thereof and when said container is dislodged from the 30 base and bellows frame, the dark slide 27 will protect the film which has been drawn from the container.

In order to draw film from the container, I provide the feed rolls 35 and 36, here 35 shown as each comprising a shaft provided with a coating and in practice, I have found that a rubber coating or sleeve will operate satisfactorily in that the rubber will yield sufficiently to effect a firm engagement of 40 the film and prevent slipping when the rolls are in motion. The rolls 35 and 36 are driven in unison through the medium of the gear wheels 37 and 38, the roll 36 taking motion from the roll 35 and the roll 35 being 45 under the control of the thumb knob 39 on one end and a crank handle 40 on the other end thereof. As the rolls may be driven by manual or mechanical power, the manner of communicating motion to the rolls is an 50 immaterial detail and I do not, therefore, wish to be limited with respect to the manner of applying power thereto.

The degree of rotation of the rolls or the 55 number of revolutions thereof is mechanically controlled by a toothed wheel 41 which is mounted on a stub shaft 42 projecting from the inner wall of the extended side of the container and said toothed wheel 41 meshes with the gear wheel 37 and has an 60 aperture 43 transversely therethrough at a point near its periphery although the position of the aperture is immaterial. A dog or detent 44 is pivoted on a stud or screw 45, and said detent has its nose pressed into 65 engagement with the teeth of the toothed

wheel 41 by the spring 46. The purpose of the dog or detent is to permit the toothed wheel 41 to rotate in one direction and to hold or guard it against rotation in an opposite direction for by this provision the film 70 may be drawn in the proper direction and as the rolls cannot be driven in a direction opposite to that required for drawing the film, the film could not be accidentally disengaged from the feeding rolls by a reversal 75 of the operation.

In order to arrest the feeding rolls when they have traveled a predetermined degree (in this instance until they have drawn all of the exposed portion of the film from the 80 exposing chamber and delivered it to the tray) I provide a device for engaging the toothed wheel 41 which will lock the said toothed wheel against movement until the latch for locking the wheel is released. The 85 means which I employ for accomplishing the result stated as embodied in the present form comprises a plate 47 of spring metal which has one end movably held with relation to the bottom of the floor 34 by means 90 of any suitable device here shown as a screw 48. The plate 47 has at its opposite end a pin 49 which is pressed into the aperture 43 of the wheel 41 by a spring 50 which bears against an angular extension 49^a of the said 95 pin when said aperture is brought into alignment with the pin as the wheel 41 rotates. The plate 47 has a limited movement between the under surface of the floor 34 and the bracket 51 and therefore as the wheel 100 41 rotates and the pin 49 enters the aperture, the said wheel is permitted a slight movement. After the pin enters the aperture the plate 47 is carried into engagement with the bracket 51, but when the said plate 105 contacts the bracket 51, the feeding mechanism is arrested as stated. When the feeding mechanism is to be released the push rod 52 is pressed inwardly and its inner end is provided with a head 53 which bears against 110 the edge of the plate 47. As the plate 47 has previously been oscillated under the action of the spring 50, the pressure on the push rod 52 must be sufficient to overcome the pressure of the spring and to disengage 115 the pin from the wheel 41. When such manipulation has taken place, the spring action of the plate 47 will cause the plate to return to its normal position parallel with the under surface of the floor in which position the 120 pin will be out of alignment with the aperture in the wheel 41 and the feeding mechanism will be freed for further operation.

The feeding roll 35 extends through the sides of the container or casing and I 125 show in Fig. 10 that the feeding roll 36 is mounted in a bearing 54. The feeding roll 35 has a similar bearing at each end and therefore a description of one bearing will suffice as a disclosure for both. 130

In order to permit the feeding roll 35 to have a yielding motion with respect to the feeding roll 36, the bearing 54 is formed on an angular end of a lever 55 and the said lever is pivoted on a stud or pin 56. The free end of the lever is under the pressure of a spring 57 and the spring is supported by a stud 58 and is held in action by another stud 59. The spring just described may be variously modified as will be understood by one skilled in the art.

The base 38 and bellows frame are preferably rigidly connected and the said base has rubber feet 60 which will prevent slipping of the apparatus while being operated. The base is further provided with an end 61 hinged in place in order that it may be swung to an open position. A tray is applied to the interior of the base through the open end thereof and said tray is designed for holding liquids which will act on the coated surface of a film.

The tray has a double bottom—that is to say the external wall 62 is convex at its front end and has its rear end 63 extending upwardly at an angle to the bottom 64, the rear edge thereof being flanged as at 65 to form a handle for applying the tray to and removing it from the interior of the base. The top of the tray near the forward end has a hood 66 which covers a portion of the inner end and said hood has a series of curved fingers 67 extending downwardly from the under surface thereof which act as guides for the film as it is delivered to the tray. The tray is further provided with a partition 68 extending from a point a short distance from the rear edge of the hood, downwardly to a point near the bottom 64 and then rearwardly to the inner surface of the rear end 63, thus forming a space 69 between the partition and the bottom of the tray which is in communication with that portion of the tray between the front end and the partition, which space is preferably utilized for containing a fluid which will act on the coated surface of a film to develop it; whereas that portion of the tray formed by the partition and its sides may contain a liquid such as hypo which will act on the developed film for the purpose of fixing it.

The inner surface of the bottom 64 of the tray is preferably provided with corrugations 70 which extend longitudinally thereof and act to support film delivered to the tray. By the provision of the corrugations the fluid is permitted to reach the coated surface of the film and to act on it uniformly throughout its surface, whereas if the bottom of the tray is uninterrupted the development might not be uniform especially if the bottom of the tray contained a deposit of silver or the like which, as is well known, becomes freed from the film in its treatment.

In order to subject the film to the action

of fluids for the purpose of developing and fixing the same, it is necessary to subject the exposed film to the action of developing fluid for a time and then to remove the film from the developing fluid and subject it to the action of the fixing fluid. In the drawing the film is illustrated as being in that portion of the tray devoted to the fluid for developing the film whereas the next succeeding section of film is shown in Fig. 1 as being in position to be exposed to the action of light. In order to remove that portion of the film from the portion of the tray where supposedly it has been developed, I provide the frame comprising two side bars 71 and 72 connected at their front ends by a cross bar 73 and at their rear ends by another cross bar 74 to which latter cross bar a handle 75 is attached. The side bars 71 and 72 are mounted in guides 76 attached to the inner surfaces of the sides of the base and said side bars are further provided with a guiding plate 77 which is stationed a short distance from the cross bar 73 whereby a space is left between the cross bar and the guiding plate for the introduction of film to the tray. The object of the guiding plate 77 is to insure the delivery of the film to the tray in front of the partition 68. As film which is drawn from a roll is usually rather stiff and has a tendency to curl, the guiding means referred to above is desirable in an apparatus of this kind as it insures positive and satisfactory operation. A stationary knife 78 extends transversely of the base and the guiding plate 77 is preferably in vertical alignment with the cutting edge of said knife when the frame of which the side bars 71 and 72 are parts has reached the limit of its inward movement.

As a further means for guiding film from the feeding rolls to the developing tray, a shield 79 is attached to the under surface of the bottom of the container 18 and extends downwardly into the path of travel of the film below the feeding rolls. As the film has been delivered between the cross bar 73 and the guiding plate 77, a pull on the frame of which the side bars are a part will result in moving the cross bar 73 outwardly, thus drawing the film which is within that portion of the tray devoted to developing liquid over the edge of the partition. The relation the parts will assume in this operation is shown in Fig. 9. As the film is drawn over the edge of the partition, liquid which would adhere thereto by capillary attraction will be removed to a great extent and therefore developing liquid would not be carried to that portion of the tray containing the fixing fluid to any appreciable extent or to such an extent as to impair the fixing fluid. As the frame heretofore referred to is moved to a greater extent than that heretofore described, the parts will be

42
brought to the position shown in Fig. 3 wherein the film is shown as having been completely removed from that portion of the tray containing the developer and is shown 5 as released to enter that portion of the tray containing the fixing fluid. The treated film is illustrated in Fig. 4 as having been cut from that portion on the roll but prior to the severance of the said film it is stretched 10 over the fixing solution as shown in Fig. 9. During the time the frame is traveling from the forward end to the rear end of the base, the exposed and developed portion of the film is being supported by the feeding rolls, 15 but after the exposed and developed portion of the film has been drawn from that portion of the tray containing the developing fluid, it is desirable to sever so much of the film as has been treated and to that end I 20 provide a knife actuated by and under the control of the frame, which is designed to coact with the knife heretofore described.

The movable knife 80 is mounted diagonally of the base on two sliding plates 81 25 and 82 which are practically duplicates of each other. The plate 81 has longitudinally disposed slots 83 and 84 which receive the guiding pins 85 and 86 respectively, which guiding pins are anchored in the sides of 30 the base. The guiding pin 85 is of less diameter than the width of the slot in order that the plate 81 may have a slight vertical movement for the purpose of allowing the knife 80 to be pressed into operative relation with the knife 78, this pressing operation being accomplished by means of a 35 spring 87 well shown in Figs. 8 and 9. The upper edge of the sliding plate 81 is provided with a shoulder 88 near the forward 40 end thereof, and a shoulder 89 near the rear end thereof. As has been stated, these parts are duplicated on opposite sides of the base and are to be actuated by the frame of which the side bars 71 and 72 are a part, 45 said side bars having lugs 90 and 91 which engage the shoulders as the frame is reciprocated, thus actuating the plates 81 and 82 which carry the knife 80. As, therefore, the frame is moved outwardly to an extent 50 farther than that shown in Fig. 9 and the treated film is wholly withdrawn from that portion of the tray containing the developer, and the lugs 90 and 91 engage the shoulders of the sliding plates 81 and 82, continued 55 movement of the frame will result in bringing the knife 80 into operative engagement with the knife 78 for the purpose of cutting the treated portion of the film, as shown in Fig. 4.

60 In order to submerge the print into the fixing fluid contained in a tray, I provide a plunger in which cranked arms 92 and 93 have their ends mounted in the bosses 94 and 95 extending from the bars 71 and in the bosses 96 and 97 extending from the bar

72. The arm 93 is held normally depressed or in the position shown in Fig. 2 by a spring 98 and as the arms 92 and 93 are connected, motion communicated to the arm 93 by the spring 98 will also be communicated to the arm 92. Links 99 are mounted on the arms and the said arms and links form a frame which is forced into that portion of the tray containing fixing fluid when the frame of which the side bars 71 and 72 are parts is moved from the position shown in Fig. 4, to the position shown in Fig. 8. During the outward movement of the said frame, the arms 92 ride over the rear surfaces of the rear end of the tray and thus 75 the arms are elevated to a position parallel with the sliding bars, but on the return movement of the frame, the spring 98 acts to depress the arms 92 and 93 as stated. In order to limit the upward movement of the 80 arms 92 and 93 and prevent them from passing the pivotal center, an abutment 100 is applied to the guiding plate 77 against which the arm 92 will strike.

In order to guide the knife 80 and cause 90 it to assume operative relation to the knife 78, the knife 80 is provided with a heel 101 which has a camming surface slightly lower than the cutting edge of the knife 80 which camming surface first engages the under 95 surface of the knife 78 and guides the cutting edges of the two knives in order that they will perform a shearing action in cutting the film.

I claim—

1. In a photographing and developing apparatus, means for exposing film to light, a container for fluid designed to act on the coated surface of the film, means for delivering film from the means for exposing it to 105 light to the container and supporting said film therein, means for drawing the supported film from the container, and means for cutting the film.

2. In a photographing and developing 110 apparatus, means for exposing film to light, a container for liquid, means for delivering the film to the container and for supporting said film in the container, means for drawing the film from the container, a second 115 container to which the drawn film is delivered, and means for cutting the film.

3. In a photographing and developing apparatus, an inclosing casing adapted to contain a supply of film and having means for exposing said film to the action of light, trays within the casing adapted to contain fluid for treating the film, means for drawing film from said exposing chamber and projecting it into one tray, a reciprocable 120 member for drawing said film from one of the trays and delivering it to the other tray, and means for severing the film.

4. In a photographing and developing apparatus, means for exposing film to light, 125

fluid receptacles, means for drawing film from the exposing means and projecting the same into one receptacle, reciprocating means for drawing film from one receptacle and moving it with relation to the other of said receptacles, means operated by said reciprocating means for severing the film, and means operated by the said reciprocating means for submerging the film in the second mentioned receptacle.

5. In a photographing and developing apparatus, means for exposing film to light, means for drawing film from the means for exposing it to light, a container to which the film is delivered, means for drawing the film from the container, a second container to which the film is delivered, means for cutting the film, means for operating the cutting means, and means carried by the cutter operating means for submerging the film.

6. In a photographing and developing apparatus, means for exposing film to light, means for drawing film from the means for exposing it to light, a container for fluids adapted to act on the coated surface of the film, a knife in position to act on the film, plates on which the knife is mounted, said plates having slots, guiding pins in the slots for supporting the plates, a knife with which the first mentioned knife co-acts, means for yieldably holding the knives in operative relation, means for reciprocating the plates, and means for drawing film from the container operated by the reciprocating plates.

7. In a photographing and developing apparatus, means for exposing film to light, a container for fluid; means for delivering film to the container, a sliding frame engaging the film to draw it from the container, and a knife for severing the film actuated by the film drawing means.

8. In a photographing and developing apparatus, means for exposing film to light, a container for fluids designed to act on the coated surface of the film, a frame mounted to reciprocate with relation to the container and having means for engaging the film to draw it from the container, and a knife operated by the frame.

9. In a photographing and developing apparatus, means for exposing film to light, a container for fluids, designed to act on the coated surface of the film; a frame mounted to reciprocate with relation to the container and having means for engaging the film to draw it from the container, a knife operated by the movement of the frame, and a plunger carried by the frame for submerging the film.

10. In a photographing and developing apparatus, a base, a bellows frame thereon, a magazine having mountings for a roll of sensitized material, the said magazine being re-

movably secured to the bellows frame and base, means for drawing film from the magazine, a container for fluid adapted to act on the film in the base to which film is delivered and in which it is supported by the drawing means, and means for removing film from the container.

11. In a photographing and developing apparatus, a base, a bellows frame thereon, a magazine removably secured to the bellows frame and base, means for drawing film from the magazine and supporting the drawn film, a container for fluid in the base to which film is delivered, a sliding frame for removing film from the container, and means actuated by the sliding frame for cutting the film.

12. In a photographing and developing apparatus, a bellows frame, a base on which the bellows frame is mounted, a magazine removably secured to the bellows frame and base, means for drawing film from the magazine and supporting it, a container for fluid to which the film is delivered, a sliding frame engaging the film for removing it from the container, sliding plates, means on the sliding frame for engaging the sliding plates, a knife carried by the sliding plates, and means on the sliding plates engaged by the sliding frame whereby the movement of the sliding frame is communicated to the sliding plates.

13. In a photographing and developing apparatus, a base, a magazine, and means for exposing film to light mounted in operative relation, means for drawing film from the magazine to the means for exposing it to light, a container for fluids to which film is delivered by the drawing means, a reciprocating member for removing the film from the container and means for cutting the film.

14. In a photographing and developing apparatus, a base, a magazine, means for exposing film to light, means for drawing film from the magazine through the means for exposing it to light, a container for fluid in the base to which the film is delivered by the drawing means and in which it is supported by the drawing means, a member independent of the film drawing means slidable in the base for drawing film from the container, and means for cutting the film operated by said member.

15. In a photographing and developing apparatus, a magazine, means for exposing film to light, means for drawing film from the magazine through the means for exposing it to light, a container for fluid to which the film is delivered by the means for drawing it, the said drawing means supporting the film in the container, a member slidable with relation to the drawing means for removing the film from the container while it is supported by the drawing means, and means for cutting the film.

16. In a photographing and developing

apparatus, a magazine, means for exposing film to light, means for drawing film from the magazine through the means for exposing it to light, a container in which film is treated, means for supporting the film free of the bottom of the container, and means for withdrawing the film from the container.

17. In a photographing and developing apparatus, a magazine, means for exposing film to light, means for drawing film from the magazine through the means for exposing it to light, the said drawing means acting to support the exposed portion of the film, a container for fluid to which the film is delivered and in which it is supported, a member slidable with relation to the container having means for engaging film to remove it from the container, knives for cutting the film, and means whereby the knives are operated by the sliding member.

18. In a photographing and developing apparatus having means for containing a supply of film and means for exposing said film to light, means for drawing said film through the exposing means from the source of supply, a developing fluid receptacle below said drawing means, a fixing fluid receptacle adjoining the same, said drawing means being adapted to project the film in the developing fluid receptacle, reciprocating means for drawing said film from the developing fluid receptacle into the fixing fluid receptacle, means for severing the film, and means actuated by the reciprocating means for submerging the film.

19. In a photographing and developing apparatus, a magazine for film, means for exposing film to light, means for drawing film from the magazine through the means for exposing it to light, the said drawing means acting to support the exposed portion of the film, a developing fluid container to which the film is delivered and in which it is supported, a fixing fluid container, a member slidable with relation to the containers having means for engaging the film to remove it from the developing fluid container and for delivering it to the fixing fluid container, knives for cutting the film, and means whereby the knives are operated by the sliding member.

20. In a photographing and developing apparatus, a magazine, means for exposing film to light, means for drawing film from the magazine through the means for exposing it to light, a developing fluid container to which the film is delivered by the means for drawing it, a reciprocating member movable with relation to the drawing means for removing film from the developing fluid container while it is supported by the drawing means, means for cutting the film, and means operated by the reciprocating member for submerging the film.

21. In a photographing and developing

apparatus, a magazine, means for exposing film to light, means for drawing film from the magazine to the means for exposing it to light, a container for fluid to which film is delivered by the drawing means, a second container for fluid, a reciprocating member for removing film from the first mentioned container and delivering it to the second mentioned container, and means operated by the reciprocating member for cutting the film.

22. In a photographing and developing apparatus, a magazine, means for exposing film to light, means for drawing film from the magazine to the means for exposing it to light, a container for fluid to which film is delivered by the drawing means, a second container for fluid, a reciprocating member for removing film from the first mentioned container and delivering it to the second mentioned container, means operated by the reciprocating member for cutting the film, and means operated by the reciprocating member for submerging the film.

23. In a photographing and developing apparatus, means for exposing film to light, a container, means for delivering film from the exposing means to the container, film drawing means including a sliding frame engaging the film to draw it from the container, and a knife for severing the film actuated by the film drawing means.

24. A photographic and developing machine comprising a suitable box provided with an opening for exposing sensitized paper, means within the box to contain developing and fixing solutions, means for feeding the sensitized paper after exposure into the developing solution, means for withdrawing the paper from the developing solution and stretching it over the fixing solution, and means for severing the paper to permit it to fall into the fixing solution.

25. A photographic and developing machine comprising a suitable box provided with an opening for exposing sensitized paper, means within the box to contain developing and fixing solutions, means for feeding the sensitized paper after exposure into the developing solution, means for withdrawing the paper from the developing solution and stretching it over the fixing solution, means actuated by the means for withdrawing the sensitized paper from the developing solution and stretching it over the fixing solution, for severing the paper to permit it to fall into the fixing solution.

26. A photographic and developing machine comprising a suitable box having an opening for exposing sensitized paper, a pan within the box having a pair of superposed chambers, the lower one extending

beyond one end of the upper one, means for feeding the sensitized paper after exposure into the extended end of the lower chamber of the pan, means for withdrawing the paper from said chamber and stretching it over the upper chamber, and means for severing the paper adjacent to the exposed end of the lower chamber to permit the detached end of the paper to fall into the upper chamber.

27. A photographic and developing machine comprising a suitable box provided with an opening for exposing sensitized paper, means within the box to contain developing and fixing solutions, means for feeding the sensitized paper after exposure into the developing solution, means adapted to slide from a point forward of the feeding means and the means containing the fixing solution over said last named means to engage the paper and withdraw it from the lower or developing solution and stretch it over the fixing solution, and means for severing the paper between the feeding means and the solution containing means to permit it to fall into the fixing solution.

28. A photographic and developing machine comprising a suitable box having an opening, a guide roll for film contiguous to the upper end of said opening, feed rolls for film contiguous to the lower end of said opening, the said feeding means being adapted to feed the paper after exposure into the lower or developing solution,

means for withdrawing the paper from the developing solution and stretching it over the fixing solution, and means to sever the paper below the feeding means to permit the severed portion to fall into the fixing solution.

29. A photographic and developing machine comprising a box having a front chamber provided with an opening in its rear wall and a door controlling the front end of said chamber, receptacles adapted to contain developing and fixing solutions, feeding means for engaging a web of paper of a roll between the said opening and the said solution containing means, means to cooperate with the feeding means for causing the web of paper to be stretched across said opening to be exposed therethrough, said feeding means being adapted after the exposure of the paper to feed the same down into the developing solution, means for reciprocating in a plane between the feeding means and the means containing the solution to draw the paper from the developing solution and stretch it over the fixing solution, and means to sever the paper adjacent to the feeding means to permit the detached portion to drop into the fixing solution.

In testimony whereof, I hereunto affix my signature in the presence of two witnesses.

GEORGE C. BEIDLER.
